(57) **CLAIM**

The ornamental design for a buffet, as shown and described.

DESCRIPTION

FIG. 1 is a perspective view of a buffet showing my new
design;

FIG. 2 is a top view thereof;

FIG. 3 is a front view thereof; and,

FIG. 4 is a right-side view thereof, the left-side view being
a mirror image.

The broken lines showing of handles are illustrative and
form no part of the claimed design.
